UNITED STATES PATENT OFFICE.

FREDERICK I. BAILEY, OF ALLSTON, MASSACHUSETTS.

DESIGN FOR A STOPPER-PLUG.

SPECIFICATION forming part of Design No. 23,091, dated February 27, 1894.

Application filed January 26, 1894. Serial No. 498,149. Term of patent 3½ years.

To all whom it may concern:

Be it known that I, FREDERICK I. BAILEY, residing at Allston, in the county of Suffolk, State of Massachusetts, have invented a new and original Design for a Stopper-Plug, of which the following is a specification, reference being had to the accompanying drawing, forming a part thereof.

The drawing represents in perspective a stopper plug showing my design.

The leading feature in my design consists in a flattened laterally extended cap having a knob-like projection upon its upper face, and a central depending stem or plug on its under face.

In the drawing I have shown a laterally extended circular flattened cap *a*, upon the upper face of which is a knob-like projection *b*, while a conical stem or plug *c* depends from the center of the under face of the cap. 20

I claim—

The design for a stopper plug, substantially as herein shown and described.

In testimony whereof I have signed my name to this specification in the presence of 25 two subscribing witnesses.

FREDERICK I. BAILEY.

Witnesses:

JOHN C. EDWARDS,
FREDERICK L. EMERY.
